CLAIM

The ornamental design for a translucent edible dough product with filling, as shown and described.

DESCRIPTION

FIG. 1 is a front view of a translucent edible dough product with filling according to our new design;

FIG. 2 is a rear view of the translucent edible dough product with filling;

FIG. 3 is a left side view of the translucent edible dough product with filling;

FIG. 4 is a right side view of the translucent edible dough product with filling;

FIG. 5 is a top view of the translucent edible dough product with filling;

FIG. 6 is a bottom view of the translucent edible dough product with filling;

FIG. 7 is a front view of a translucent edible dough product with filling according to another embodiment of our new design;

FIG. 8 is a rear view thereof;

FIG. 9 is a left side view thereof;

FIG. 10 is a right side view thereof;

FIG. 11 is a top view thereof;

FIG. 12 is a bottom view thereof;

FIG. 13 is a front view of a translucent edible dough product with filling according to another embodiment of our new design;

FIG. 14 is a rear view thereof;

FIG. 15 is a left side view thereof;

FIG. 16 is a right side view thereof;

FIG. 17 is a top view thereof;

FIG. 18 is a bottom view thereof;

(Continued)

FIG. 19 is a front view of a translucent edible dough product with filling according to another embodiment of our new design;
 FIG. 20 is a rear view thereof;
 FIG. 21 is a left side view thereof;
 FIG. 22 is a right side view thereof;
 FIG. 23 is a top view thereof;
 FIG. 24 is a bottom view thereof;
 FIG. 25 is a front view of a translucent edible dough product with filling according to another embodiment of our new design;
 FIG. 26 is a rear view thereof;
 FIG. 27 is a left side view thereof;
 FIG. 28 is a right side view thereof;
 FIG. 29 is a top view thereof;
 FIG. 30 is a bottom view thereof;
 FIG. 31 is a front view of a translucent edible dough product with filling according to another embodiment of our new design;
 FIG. 32 is a rear view thereof;
 FIG. 33 is a left side view thereof;
 FIG. 34 is a right side view thereof;
 FIG. 35 is a top view thereof;
 FIG. 36 is a bottom view thereof;
 FIG. 37 is a front view of a translucent edible dough product with filling according to another embodiment of our new design;
 FIG. 38 is a rear view thereof;
 FIG. 39 is a left side view thereof;
 FIG. 40 is a right side view thereof;
 FIG. 41 is a top view thereof;
 FIG. 42 is a bottom view thereof;
 FIG. 43 is a front view of a translucent edible dough product with filling according to another embodiment of our new design;
 FIG. 44 is a rear view thereof;
 FIG. 45 is a left side view thereof;
 FIG. 46 is a right side view thereof;
 FIG. 47 is a top view thereof; and,
 FIG. 48 is a bottom view thereof.

The smaller stippled shading and larger stippled shading shown in the drawings represent a contrasting appearance.
